CLAIM

The ornamental design for an eyeglass, as shown and described.

DESCRIPTION

FIG. 1 is a front perspective view of the eyeglass of the present invention;

FIG. 2 is a front perspective view of the eyeglass of the present invention, with a magnified view of a portion thereof;

FIG. 3 is a front elevational view thereof;

FIG. 4 is a rear elevational view thereof;

FIG. 5 is a left-side elevational view thereof, the right-side elevational view being a mirror image thereof;

FIG. 6 is a top plan view thereof;

FIG. 7 is a bottom plan view thereof;

FIG. 8 is a front perspective view of an alternative embodiment of the eyeglass of the present invention;

FIG. 9 is a front perspective view of the eyeglass of FIG. 8, with a magnified view of a portion thereof;

FIG. 10 is a front elevational view of the eyeglass of FIG. 8;

FIG. 11 is a rear elevational view of the eyeglass of FIG. 8;

FIG. 12 is a left-side elevational view of the eyeglass of FIG. 8, the right-side elevational view being a mirror image thereof;

FIG. 13 is a top plan view of the eyeglass of FIG. 8; and,

FIG. 14 is a bottom plan view of the eyeglass of FIG. 8.
